Filed July 13, 1964, Ser. No. 80,835

Term of patent 7 years

(Cl. D45—4)

FIG. 2

FIG. 1

FIG. 3

FIG. 4

FIG. 5

FIG. 6

FIG. 1 is a top plan view of a link chain for a bracelet showing my new design;

FIG. 2 is a top plan view on an enlarged scale of one of the links of the link chain of FIG. 1;

FIG. 3 is a top plan view on an enlarged scale of one of the links of the link chain of FIG. 1 located adjacent to the link of FIG. 2;

FIG. 4 is a side elevational view of the top shell of the link of FIG. 2, taken from the right hand side thereof;

FIG. 5 is a side elevational view of the link of FIG. 3, taken from the right hand side thereof; and

FIG. 6 is an end elevational view of the top shells of the links of FIGS. 2 and 3.

The shading shown in the central area of the links in FIGS. 1, 2 and 3 is intended to indicate contrast.

I claim:

The ornamental design for a link chain for a bracelet or the like, as shown and described.
